INVENTOR

BY Victor J. Evans

ATTORNEY

UNITED STATES PATENT OFFICE.

FRANK J. STEZZEWSKI, OF CHICAGO, ILLINOIS.

BAIL TIE.

Application filed July 2, 1927. Serial No. 203,160.

This invention relates to certain novel improvements in rail ties.

The salient object of the invention is to provide a tie which may be embedded in the earth of a railroad road bed and which will be so arranged that the rails may be expeditiously secured thereto.

Another object of the invention is to provide a railroad tie which may be constructed of cast metal.

A further object of the invention is to provide a railroad tie of the above described type which will be arranged in such a manner that drainage of the road bed will be materially aided.

Other objects will appear hereinafter.

The invention consists in the novel combination and arrangement of parts to be hereinafter described and claimed.

The invention will be best understood by reference to the accompanying drawings, showing the preferred form of construction and in which:

Fig. 1 is a plan view of a railroad track-way embodying a preferred form of my invention;

Fig. 2 is a sectional view taken substantially on the plane of the line 2—2 on Fig. 1;

Fig. 3 is a perspective detail view of a preferred form of tie construction employed in my invention;

Figs. 4 and 5 are elevational views of modified forms of tie constructions; and

Fig. 6 is a sectional detail view taken substantially in the plane of the line 6—6 on Fig. 2.

Referring to the drawings wherein the preferred embodiment of my invention is illustrated it may be seen that I depict a railroad trackway comprised of rails 1 and 2 carried by ties 3 that are adapted to be embedded in the earth of a railroad right-of-way road bed generally indicated by 4 in the drawings.

By referring to Fig. 2 it may be seen that the ties 3 are embedded in the road bed 4 in such a way that a portion thereof extends above the earth level of the road bed. On the upper side of the ties 3 in the mid-portion thereof a trough 5 is formed. The trough 5 serves to drain off rainfall and the like. This construction is such that the drainage will be so controlled that the carrying off of the material comprising the road bed will be reduced since portions of

the ties protrude above the level of the road bed. The drainage flows through the troughs in the succeeding ties and due to the upwardly protruding portions of the ties it is apparent that the drainage will be directed so that very little of the road bed will be washed away.

In the tie 3 on each side of the trough 5 recesses 6 are provided. These openings are preferably so arranged that the lower walls thereof are in alignment with the earth level of the road bed 4 when the tie is properly positioned. The recesses 6 are spaced apart in the ties a distance such that the center lines thereof are spaced apart an amount equal to the distance between the center lines of the rails that are adapted to be mounted thereon. As is clearly shown in Fig. 6, webs 7 are disposed between each pair of recesses so as to increase rigidity of the upper side of the tie in the region of said recesses 6.

In the upper side of the ties 3 and extending into the recesses 6 are openings 8 which are arranged so as to be juxtaposed with the rails adapted to be mounted on the ties. L-shaped securing elements 9 are arranged so that the stem portion thereof protrudes through the openings 8 into the recesses 6 and so that the head portions thereof engage the foot portions 10 of the rails 1 and 2. The securing elements 9 have openings 11 provided therein through which the wedge shaped key elements 12 are adapted to extend. As is clearly shown in Fig. 2 the key elements 12 have wedge shaped portions on the lower side thereof while the side opposite said wedge shaped portion is made substantially flat and is adapted to engage the upper wall of the recesses 6.

As has been stated the recesses 6 are disposed above the ground level of the road bed 4 and therefore easy access may be had at all times. A suitable tool is used in order to force the wedge elements tightly into the openings 11 in order to fasten the L-shaped securing elements in position and thus securely fasten the rails to the ties.

As has been stated the ties 3 are preferably composed of cast metal which as is obvious will afford a very economical method of manufacture. It is to be understood however that other forms of material might be employed in the tie construction if so desired. In Fig. 5 a modified form of tie con-

- struction over that disclosed in Fig. 3 is depicted. In this instance the tie 3' embodies a trough 5' which is made so as to be substantially rectangular in contra-distinction 5 to the substantially V-shaped trough 5 provided in the tie 3. In Fig. 4 a further modified form of tie construction is disclosed and the form depicted herein comprises a tie 3'' which is constructed without the trough 5. 10 This form of construction would be used where the drainage problem would be minor and is depicted for the purpose of showing that my improved tie construction is not limited to the embodiment of a trough. 15 It is apparent from the foregoing description that I have provided a means for mounting the rails of a railroad trackway in position which include a tie that may be very economically manufactured and one to 20 which the rails may be secured in a very expeditious manner.

While I have illustrated and described the preferred form of construction for carrying my invention into effect, this is capable of variation and modification without departing from the spirit of the invention. I, therefore do not wish to be limited to the precise details of construction set forth, but desire to avail myself of such variations and 25 modifications as come within the scope of the appended claims.

Having thus described my invention what I claim as new and desire to protect by Letters Patent is:

- 35 1. A railroad tie of cast metal having spaced apart recesses in the sides thereof juxtaposed the upper edge, the upper side of said tie having a depression formed therein disposed between said recesses, the lower

walls of said recesses and said depression 40 being in alignment.

2. In combination with the roadbed of a railway, ties adapted to be embedded in the earth of said roadbed so as to have portions thereof disposed above the level of said 45 roadbed, spaced apart rails on said ties, said ties having openings therein disposed below said rails in the portions of said ties disposed above said roadbed so as to afford access to means employed for securing said rails to 50 said ties, said ties having depressions formed in the upper side thereof between said rails, said depressions serving as drainage troughs for said roadbed, the lower walls of said recesses and said depressions being disposed in 55 alignment with the earth level of said roadbed.

3. A cast railroad tie having recesses formed in opposed edges thereof adjacent the ends, said recesses having a rib formed 60 therebetween and being disposed adjacent the upper edge of said tie, said tie having a depression formed in the upper edge thereof intermediate said recesses and arranged 65 to have the lower edge thereof in substantial alignment with the lower edge of said recesses, and said tie having openings formed in the upper side thereof arranged in spaced apart relation and adapted to extend into said recess, said last named openings being spaced apart a distance substantially equal to the width of a rail whereby 70 securing elements may be inserted through said openings to engage said rail so as to retain it in position on said tie.

In testimony whereof I affix my signature.

FRANK J. STRZYZEWSKI.
